C. F. ROBINSON

COMBINATION ASH TRAY, MATCH BOX, AND CIGARETTE PACKAGE HOLDER

Filed May 29, 1923

UNITED STATES PATENT OFFICE.

CLYDE FRANK ROBINSON, OF MIAMI, OKLAHOMA.

COMBINATION ASH TRAY, MATCH BOX, AND CIGARETTE-PACKAGE HOLDER.

Application filed May 29, 1923. Serial No. 642,243.

To all whom it may concern:

Be it known that I, CLYDE F. ROBINSON, a citizen of the United States, residing at Miami, in the county of Ottawa and State of Oklahoma, have invented certain new and useful Improvements in Combination Ash Trays, Match Boxes, and Cigarette-Package Holders, of which the following is a specification, reference being had to the accompanying drawings.

This invention relates to receptacles, and particularly to a combination ash tray, match box, and cigarette package holder.

The general object of this invention is to provide a device which will hold a match box, a cigarette package, and also hold an ash tray in place on the instrument board of an automobile.

A further object is to provide a device of this character in which the ash tray may be shifted to a fully closed or fully open position whenever desired, the ash tray being further entirely removable from the supporting frame of the device so as to empty it.

A still further object is to provide a device of this character in which the match box and the cigarette package are resiliently held in place in the holder or frame in the most convenient position for the motorist to secure a cigarette or a match.

Another object is to provide a device of this character in which the holder is formed of one piece of metal.

Still another object is to provide a device of this character comprising a holder adapted to be applied to the instrument board of the automobile having an opening through which a cigarette may be inserted to discharge ashes into the ash tray having a match box holder at the lower end with a portion of the side of the match box exposed so that matches may be struck thereon, and with a pocket or compartment formed behind the ash tray holder into which a cigarette package may be inserted.

Other objects will appear in the course of the following description.

My invention is illustrated in the accompanying drawings, wherein:—

Figure 1 is a perspective view of a device constructed in accordance with my invention;

Figure 2 is a detail perspective view of the ash tray or box;

Figure 3 is a vertical sectional view of the device;

Figure 4 is a rear elevation;

Figure 5 is a view of one of the blanks;

Figure 6 is a view of the blank out of which the ash tray is formed;

Referring to these drawings, it will be seen that my improved receptacle is formed, except as regards the ash tray itself, of one piece of sheet metal. This sheet metal, the blank of which is shown in Figure 5, is bent so as to provide a front 10, a top wall 11 extending rearward from the front 10, and then downward, as at 12. This downwardly projecting portion is narrower than the front plate 10. The blank is bent at the sides of the plate 10 to form the side pieces 13. These side pieces extend downward from the top 11 but terminate short of the extreme lower end of the front plate 10. The side pieces have downwardly and rearwardly inclined upper and lower edges 14 and the extremities of the side pieces are angularly bent, as at 15, and pierced so that screws may be inserted through the openings and into the instrument board A of the machine to hold the device in place. These side walls 13 are cut out at 16 and the portions of the metal so cut out are bent downward and inward, as at 17.

The front plate adjacent its lower end is cut out, as at 19, and the metal piece so cut out is bent upward and rearward, as at 20, to form a clamp. The lower end of the blank forming the front plate is angularly bent, as at 21, to form a support upon which a match box may be disposed, this match box being inserted between the tongue 20 and this supporting portion 21 and clamped in place by the tongue 20, there being so little space between the tongue 20 and the member 21 that the match box will have to be forced into place and will be yieldingly held in position against any chance of detachment.

The lower edge of the portion 12 is inwardly turned, as at 22. The front plate 10 is also formed adjacent its upper end with a segmental or nearly semi-circular opening 23 and the metal from this opening is bent outward and upward, as at 24, to form a rest or guide.

Insertible through the opening 16 and supported upon the inwardly turned member 17 is the ash tray or box, designated generally 25. This is formed of a single blank of material bent so as to form a rectangular receptacle open at its top having opposite side walls and opposite end walls. The rear wall 26 of this receptacle is longitudinally

grooved, as at 27, to receive the inwardly turned bead 22 of the portion 12. The bottom wall 28 of the receptacle extends beyond the end walls, as at 30.

5 It will be seen that in forming this receptacle, the end walls are formed by flanging the front and rear walls, these flanges overlapping each other at 31. Thus the front and rear walls will tend to more or less 10 silently expand and when these front and rear walls are forced toward each other and the ash receptacle is inserted in rectangular openings 32 formed in the side walls 13 of the holder, the walls will tend to 15 expand outward and the bead 22 will, therefore, engage the groove 27, thus retaining the ash receptacle or tray in its lowered position. The prolongation 30 of the bottom 28 will extend out beyond the side walls of the holder 20 so as to permit the ash tray to be moved up into the upper portion of the ash tray compartment with its open upper end against the top 11 of the holder if desired, thus preventing the wind from accidentally 25 blowing the ashes out of the ash receptacle. When it is desired to use the ash receptacle constantly, the ash receptacle may be drawn downward until its bottom rests upon the supporting ears 17. Under these circumstances 30 ashes may be knocked off of a cigar or cigarette upon the upwardly extending flange 24 and will be discharged by this flange into the ash tray. When it is desired to dump the ash tray, the ash tray may be shifted laterally and entirely removed from 35 the holder.

It will be noted that the sides 14 extend rearward some distance beyond the plane of the portion 12 and then are provided with 40 the laterally extending ears 15. When this device is applied to the instrument board A and held by screws through these ears 15, a space is left between the rear wall 12 and the instrument board in which a package of 45 cigarettes may be inserted, this package being held between the projecting sides 14, the instrument board, and the plate 12. Inasmuch as this plate is slightly resilient, the package will be firmly clamped in place. It 50 may rest at its lower end upon the match box which is disposed between the clamp 20 and the shelf 21.

It will be seen that this device provides a 55 holder for match boxes, cigarette packages, and a removable ash tray, and that this ash tray may be shifted from a receiving position to a closed position by a very simple movement. The device is simple, cheap, may be 60 readily applied to automobiles and other vehicles and supports a box of matches so that the matches may be readily secured from the match box and readily ignited through the opening 19 upon the prepared igniting face of the match box.

65 While I have illustrated certain details

of construction and arrangement of parts which I believe to be particularly effective, I do not wish to be limited to these as it is obvious that many changes might be made in the details of construction without departing 70 from the spirit of the invention as defined in the appended claims.

I claim:—

1. A match box, cigarette package and ash tray holder formed to provide a front and 75 two side walls, the side walls being formed at their terminations to be attached to the instrument board of an automobile, the lower end of the front plate being cut away to provide an opening for the display of the ignition surface of a match box and to provide 80 clamps between which the match box is disposed, the clamps extending rearward from said opening, the upper end of the front wall being apertured, and an ash tray insertible into the space behind the front wall and normally held in said space to receive 85 ashes discharged through said opening, the side walls extending beyond said ash tray whereby to form a compartment between the 90 ash tray and the instrument board for the reception of a package of cigarettes.

2. A match box and cigarette package holder comprising a front plate having an aperture at its lower end and an aperture at 95 its upper end and formed to provide side walls extending from the upper end of the holder nearly to the lower end thereof, the lower end of the holder being angularly flanged to provide a shelf and the material 100 cut out of the said opening being rearwardly flanged parallel to the first flange whereby to support a match box between the two flanges, the side walls below the upper opening having apertures, and an ash receiver supported by said side walls and removable through said aperture, the upper end of the ash receiver being open and being disposed below the upper opening, the side walls extending beyond said ash receiver to thereby space 105 the ash receiver from an instrument board and permit the support of a package of cigarettes between the ash receiver and the instrument board.

3. A holder of the character described 115 adapted to be attached to the instrument board of an automobile and having an ash receiving opening in its front wall, and an ash receiver mounted in said holder below the front wall and shiftable into a position to close said opening or out of such position.

4. A holder of the character described having a front wall apertured for the reception of ashes, the front wall at the lower 125 edge of the opening having an upwardly and outwardly extending flange, and an ash receiver detachably mounted in the holder rearward of said aperture, the ash receiver being removable into a position to close said 130

aperture or into a position to receive ashes through said opening.

5. A holder of the character described having a front wall provided with an aperture, the front wall below said aperture having an upwardly and forwardly inclined flange, the holder having apertured side walls, and an ash receiver normally disposed between said side walls and removable through said openings therein and being normally disposed below the opening in the front wall, the ash tray being shiftable into a position to close said opening.

6. A holder of the character described having a front wall, side walls and a top wall, the front wall having an opening, the front wall below said opening having an upwardly and outwardly extending flange, the side walls having oppositely disposed openings below said opening in the front wall, and an ash receiver open at its upper end and normally disposed between the side walls and longitudinally movable through said openings in the side walls whereby it may be removed, the ash receiver being normally disposed with its open end below the opening in the front wall but being vertically movable across said opening to close said opening and to bring the top of the ash receiver against the top of the holder to thereby close the ash receiver.

7. A holder of the character described having a front wall, side walls and a top wall, the front wall having an opening, the front wall below said opening having an upwardly and outwardly extending flange, the side walls having oppositely disposed openings below said opening in the front wall, an ash receiver open at its upper end and normally disposed between the side walls and longitudinally movable through said openings in the side walls whereby it may be removed, the ash receiver being normally disposed with its open end below the opening in the front wall but being vertically movable across said opening to close said opening and to bring the top of the ash receiver against the top of the holder to thereby close the ash receiver, the front wall being downwardly extended below the ash receiver and formed to provide rear-

wardly extending clamping members between which a match box may be disposed, the front wall being cut away to expose the ignition finish of the match box, the side walls extending beyond the ash receiver and being formed at their ends to provide means whereby the holder may be attached to an instrument board, the space between the ash receiver and the instrument board constituting a pocket to receive a cigarette package.

8. A holder of the character described comprising a front wall, side walls and a top wall, a rear wall extending downward from the top wall and formed with a bead, the side walls having oppositely disposed openings, the front wall having an opening disposed above the openings in the side walls and the lower edge of this opening being defined by an upwardly and outwardly extending flange, an ash receiver having a bottom wall, end walls, and front and rear walls and insertable through the openings in the side walls of the holder into position beneath the opening thereof, the rear wall of the ash receiver being longitudinally grooved to receive said bead and there being supporting members extending inward from the side walls at the lower ends of said openings upon which the ash receiver may rest, the bottom of the ash receiver being longer than the distance between said side walls of the holder and projecting out through said openings, the ash receiver being movable vertically upward so as to close the opening in the front wall and to bear against the top wall of the holder.

9. As an article of manufacture, a combined cigarette and match box holder and ash receiver comprising a holder adapted to be attached to the instrument board of an automobile having means for supporting a box of matches and a package of cigarettes and having a removable ash receiver, the holder being formed with an opening whereby ashes may be discharged into the receiver, the receiver being shiftable to close said opening and the receiver being removable from the holder.

In testimony whereof I hereunto affix my signature.

CLYDE FRANK ROBINSON.
